RAILWAY SIGNALING SYSTEM

Howard A. Thompson, Edgewood, Pa., assignor to
The Union Switch & Signal Company, Swiss-
vale, Pa., a corporation of Pennsylvania

Application February 17, 1940, Serial No. 319,510

7 Claims. (Cl. 246—33)

My invention relates to railway signaling systems for use on stretches of two direction running track and it has special reference to systems of this class wherein signals positioned along the wayside are controlled over line wires that extend between signal locations.

Generally stated, the object of my invention is to reduce the number of control conductors which line wire systems of railway signaling require.

A more specific object is to utilize a single pair of line wires to control signals that govern traffic in either direction.

Another object is to provide new and improved facilities for overlapping the track circuit control limits of the system signals and for approach controlling the energization of those signals.

An additional object is to protect against unsafe signal response upon an accidental crossing or breaking of the system line wires.

A further object is to make a new and novel application of the "coded feed back" principle of Frank H. Nicholson Patent No. 2,021,944.

A still further object is to provide improved apparatus for use in line and other circuits of the "coded feed back" type.

In practicing my invention I attain the above and other objects and advantages by arranging the line circuits of the signaling system to operate on the "coded feed back" principle of the above-mentioned Nicholson Patent 2,021,944; making the operation of these line circuits responsive to track relays which indicate the conditions of traffic in preselected sections of the signaled stretch; and governing the system signals by the coded energy which the thus controlled line circuits transmit.

I shall describe one form of railway signaling system which embodies the improvements of my invention and shall then point out the novel features thereof in claims. This illustrative embodiment is disclosed in the accompanying drawings in which:

Figs. 1a to 1c are diagrammatic views which, when placed end to end in the order named, show a stretch of two direction running track that is equipped with an overlap signaling system controlled in accordance with the teachings of my invention;

Fig. 2 is a single line diagram showing the limits of track circuit control for each of the several wayside signals in the system of Fig. 1;

Fig. 3 is a representation of one of the "coded

feed back" line circuits by which the signals of Fig. 1 are controlled; and

Fig. 4 is a representation of "Master" and "Feed back" codes which are suitable for operating the line control circuits of Figs. 1 and 3.

In the several views of the drawings like reference characters designate corresponding parts. To facilitate the description of the various circuit diagrams of these views, it will be assumed that the left end thereof is west and the right end east. Hence, train movements in the direction of from left to right will be spoken of as "eastbound" and movements in the direction of from right to left will be spoken of as "westbound".

Referring first to the composite diagram of Figs. 1a-c, the improvements of my invention are there disclosed as being incorporated in an opposing overlap system of wayside signaling for a stretch of single track 1—2 over which traffic may move in either direction. At suitable intervals along this stretch the usual passing sidings PS (only one is shown in Fig. 1) are provided. These sidings permit traffic to be diverted from the main track (under the customary control of end switches W) at proper times.

The rails of this two direction running stretch of single track 1—2 are divided by the usual insulated joints 3 into the customary plurality of successive track sections I—II, II—III, III—IIIa, IIIa—IV, etc. and the rails of each of these sections form a part of a steady energy track circuit which includes a track battery TB at one end of the section and a track relay TR at the opposite end. Each of these track relays responds to the traffic conditions of the associated section in the customary manner; that is, the relay stays picked up as long as the section remains vacant and releases when the section becomes occupied.

Positioned at the locations I, II, III, IV, VI and VIII are wayside signals SE which are arranged to govern eastbound traffic through the track stretch. Similarly installed at the locations VII, V, IV, III, II and I are other wayside signals SW which are arranged to govern the passage of westbound trains over the track. The signals first named will be designated by the term "eastbound" while those last named will be designated by the term "westbound".

These eastbound and westbound signals may, of course, be of any suitable form, such as of the color light type of Fig. 1 or the semaphore type of Fig. 2. In either case certain of them are "home" devices which display one or another of

the indications of "clear" and "stop" while the remaining are "distant" devices which display one or another of the indications of "clear" and "approach."

Included in the former or "home" signal class are the square ended semaphores SE—I—III—IV—VI and SW—VIII—IV—III—II of Fig. 2 and the corresponding G—R (green—red) color light signals of Fig. 1; included in the latter or "distant" signal class are the notch ended semaphores SE—II—III—VIII and SW—V—IV—I of Fig. 2 and the corresponding G—Y (green—yellow) color light signals of Fig. 1.

In the composite diagram of Fig. 1 certain non-signal locations of track section division have also been shown. These are designated as III_a, Va and VII_a and each marks a cut in the main signal block in which it is included. Such cuts may, of course, be occasioned by excessive block lengths, by highway intersections (not shown) or for any other reason; due to their special character they have no wayside signals associated therewith.

As herein represented, the just named cut locations are utilized by the opposing overlap scheme of signal control in connection with which the improvements of my invention are disclosed. For an understanding of the basic features of this scheme reference to the control limit diagram of Fig. 2 may be made.

In that diagram the thin arrow lines emanating from the large "dots" at the signal locations indicate the limits of track circuit control for the wayside signals with which these lines are identified. For example, eastbound "home" signal SEIII which guards block III—IV is controlled as far to the east as location V and westbound "home" signal SWIV which guards the same block is controlled as far to the west as location II; eastbound signal SEIV at the west end of track length IV—VII is controlled as far to the east as cut location VII_a and westbound signal SWVII at the east end of the same track length is controlled as far to the west as location IV; etc.

It will be seen, therefore, that in its broader aspects this "overlap" arrangement of Fig. 2 is conventional in that: (1) the control of each "home" signal is extended beyond the next signal in advance (which governs in the same direction) for at least braking distance; and (2) the function of this overlapped control is to prevent opposing trains from entering the same block at the same time and colliding head on. Inasmuch as the broad principles of overlap control are well known in the art, no further description of them will here be attempted.

The improvements of my invention are directed to the facilities by which the "overlap" control of Fig. 2 and other equivalent forms of signal governing may be effected. As shown in Fig. 1, these facilities include line circuits which extend between signal locations in conventional manner and which transmit energy for controlling the system signals.

Coded line circuits

In the organization of apparatus and circuits which I have shown in Fig. 1, the relation of the line circuits to the controlled signals is as follows: A first circuit including line wires 5 and 6 transmits the energy by which signal SWI is controlled; a second circuit including line wires 7 and 8 transmits the energy by which signals SEI, SWII and SWIII are controlled; a third

circuit including line wires 9 and 10 transmits the energy by which signal SEII is controlled; a fourth circuit including line wires 12 and 13 transmits the energy by which the "home" units

- 5 G—R of signals SEIII and SWIV are controlled; a fifth circuit including line wires 14 and 15 transmits the energy by which the "distant" units G—Y of signals SEIII and SWIV are controlled; a sixth circuit including line wires 16
- 10 and 17 transmits the energy by which the signals SEIV and SWVII are controlled; a seventh circuit including line wires 18 and 19 transmits the energy by which signal SWV is controlled; an eighth circuit including line wires 20 and 21 transmits the energy by which signal SEVI is controlled; and a ninth circuit including line wires 22 and 23 transmits the energy by which signal SEVIII is controlled.

The signal control energy which each of the 20 nine line circuits of Fig. 1 transmits is periodically interrupted or "coded" and it thus takes the form of recurring "on" period pulses that are separated by "off" period intervals. While these pulses may recur at any suitable rate, code speeds 25 of 75 and 180 pulses per minute are preferred. One obvious advantage of selecting such standard rates is that the coding of the line circuit energy then may be effected by code transmitters of the conventional type represented at CT75 and CT180 in Fig. 1. When such transmitters are used codes of the characters shown in Fig. 4 are produced.

In regard to the number of different forms of 35 coded energy which the circuit conductors transmit, various of the line circuits of Fig. 1 differ from the remaining. In the case of each of the line circuits 5—6, 9—10, 18—19 and 22—23, this transmitted energy is of the "Master 75" code of Fig. 4 only; in the case of each of the line circuits 7—8, 16—17 and 20—21, it is of both the "Master 75" and the "Feed back 75" codes; and in the case of each of the line circuits 12—13 and 14—15, it is of the "Master 75" and the "Feed back 75" codes at times and of the "Master 40 180" and "Feed back 180" codes at other times.

The single-code group of line circuits 5—6, 9—10, 18—19 and 22—23 of Fig. 1 will first be considered. Looking particularly at the completely represented circuits 9—10 and 18—19 of this group, it will be seen that each of these single-code circuits is energized from a master battery MB; that the conductors of the circuits are periodically connected with that battery by contacts 75 of the associated code transmitter 55 CT75; and that these conductors transmit the recurring pulses of line code energy to a master line relay MR installed as shown at the opposite end of the circuit.

This master line relay MR is a code following 60 device and in customary manner it picks up and releases in step with the "on" and the "off" periods of the line code energy which its winding receives. This code following action, in turn, is utilized to perform certain signal control functions that later will be described.

Normally, all of the previously named single-code line circuits are maintained intact and under that condition all of the master relays MR thereof follow code continuously. At times, 70 however, each of these circuits is interrupted for the purpose of discontinuing the code following action just stated and thereby changing the signal governing condition in a manner later to be made evident.

75 For the present, it will suffice to say that in

the case of line circuit 9-10 this interruption takes place at location III and is effected either by contacts 30 of a relay TP (later to be described) or by contacts 31 of a relay H (also later to be described); in the case of line circuit 18-19 the named interruption takes place at location IV and is effected either by contacts 32 of the track relay TR for section IV-V or by contacts 33 of a relay H180 (later to be described); and so on.

The double-code group of line circuits 7-8, 16-17 and 20-21 of Fig. 1 will next be considered. From an inspection of the completely represented circuit 16-17 of this group, it will be seen that each of these double-code circuits makes use of a master battery MB at one end thereof; that the conductors of the circuit are periodically connected with this battery by contacts 75a of the associated code transmitter CT75; and that these conductors transmit recurring pulses of master energy to a master code following relay MR at the opposite end of the circuit. For a purpose later to be made evident, this master relay MR is polarized in the manner indicated by the "plus" and "minus" markings therefor.

The several elements just named correspond to and function in the same manner as those already described in connection with the single-code line circuits. That is, relay MR follows the coding of the "Master" energy which battery MB supplies thereto over the code transmitter contacts and the line circuit conductors.

In addition, each double-code line circuit includes supplemental facilities by which the before-mentioned "Feed back" code is supplied and utilized. In the case of circuit 16-17 these supplemental facilities include a feed back battery FB at what will be termed the "Feed back" end of the circuit (which is remote from the master battery end); a similarly located feed back coder relay FC; and a feed back energized relay FR installed at what will be termed the "master" end of the circuit (which marks the location of the master battery MB).

This master end relay FR is a code following device and it is arranged to receive operating energy from the feed back battery FB at the opposite end of the circuit. During each "off" period of the "Master" code which the master end transmitter CT75 produces this relay is connected with the line circuit conductors over the back points of the transmitter contacts 75a. During, however, the "on" periods of the thus produced master code, the same contacts disconnect the relay from the circuit conductors and thus prevent it from receiving energy from the master battery MB.

The feed back end coder relay FC also is a code following device and it receives pick-up energy over the front points of a pair of contacts 35 of the master code following relay MR. Under the action of a snubbing resistor 36 it is given a period of release delay which is somewhat less than the length of the master "off" periods and which is designated as "k" in Fig. 4.

In their released position, the same master relay contacts 35 set up a circuit over which the feed back battery is connected in energy supplying relation with the line circuit conductors. Included in this feed back supply circuit are a pair of contacts 37 of the feed back coder relay FC. These contacts must be picked up before the supply circuit can be completed and they interrupt that circuit whenever they are released.

The just named elements MR, FC and FB at the "feed back" end of the line circuit cooperate in the following manner. Each "on" period pulse of "Master" code energy that is there received from the line circuit conductors picks up the master relay MR and connects the coder relay FC with those conductors over front contact 35. Now also energized by the master energy pulse, that coder relay picks up and sets up the above-mentioned feed back supply circuit at front contacts 37. That circuit, however, continues to be interrupted at the back point of contact 35.

At the end of the master code "on" period (and the beginning of the succeeding master code "off" period), master relay MR releases these contacts 35 and thereby connects the feed back battery FB across the line circuit conductors over the front point of contact 37 of the slow release coder relay FC. Once this connection is established in the manner just stated, it continues intact for the full release period "k" (see Fig. 4) of the coder relay. At the end of that period contacts 37 release and disconnect the feed back battery from the line circuit conductors.

It will thus be seen that during each "off" period of the "Master" code energy which the line circuit transmits to the feed back end thereof, a pulse of "Feed back" code energy is supplied to the conductors of that circuit. As already indicated, the length of each of these feed back pulses is slightly less than the length of the master code "off" period during which the pulse is supplied.

In the arrangement represented the master code following relay MR is prevented from being falsely picked up by those feed back pulses by causing the energy of which they are constituted to have an opposing polarity relation to the recurring pulses of master code energy to which the master relay does respond. This opposing relation is indicated by the polarity markings on devices FB and MR.

Each of the "off" period pulses of the feed back energy that is thus supplied to the line circuit in the manner above stated is transmitted over the circuit to the opposite or master end thereof. There it is impressed upon the before described feed back code following relay FR over the back points of code transmitter contacts 75a. That relay FR responds in the usual code following manner to the recurring pulses of feed back energy which its winding receives and performs signal control functions later to be described.

It will accordingly be seen that each of the double-code line circuits 7-8, 16-17 and 20-21 embraces the facilities of two separate coded line circuits which include the line circuit conductors as common elements and which operate simultaneously on these conductors. One of these coded circuits transmits recurring pulses of "Master code" energy over the line conductors in one direction and it will be referred to as the first or "Master" line circuit; the other transmits "off" period pulses of "feed back" energy over the line conductors in the opposite direction and it will be referred to as the second or "feed back" line circuit. To designate both of these simultaneously operating line circuits, use will be made of the expression "coded feed back" line circuit combination.

One basic application of such a combination to the rails of a track section is disclosed and

claimed in the before referred to Nicholson Patent 2,021,944. The present application of the "coded feed back" principle to line circuits is unique in that responsiveness to traffic conditions of the associated track stretch is effected through the medium of contacts which are interposed directly in the circuit itself and which are operated by a track relay or other device of the character shown at TR in Fig. 1.

In the case of the "coded feed back" line circuit 16-17, such circuit interrupting contacts are represented at 39, 40, 41, 42 and 43; in the case of the companion two-code line circuit 7-8, corresponding contacts are shown at 44 and 45; and in the case of the third two-code line circuit of Fig. 1, similar traffic responsive contacts are shown at 46, 47, 48 and 49.

Normally (and as is represented in Fig. 1), all of the just named contacts are picked up and under that condition the operation of each of the "coded feed back" line circuits 1-8, 15-17 and 20-21 of the two-code group is as follows. The code transmitter CT15 at the master end recurrently picks up and releases its contact 75a at the before stated rate of 75 times per minute. Each pick-up of these contacts causes the source MB to impress upon the line conductors a pulse of master code energy which is transmitted over those conductors to the master line relay MR at the opposite or feed-back end of the circuit.

Each pick-up of relay MR connects (over front contact 35) the feed back coder relay FC across the line conductors and causes it also to receive the master energy pulse. That relay now picks up and sets up at contacts 37 a circuit over which the feed back source FB supplies the line conductors with a pulse of feed back energy during the succeeding master code "off" period.

This feed back pulse is impressed upon the line conductors when contacts 75a of transmitter CT at the master end of the circuit go to their lowermost positions and thus deenergize the master relay MR at the opposite or feed back end of the circuit. When that happens, contact 35 of relay MR disconnects the coder relay FC on the line conductors and completes the above-mentioned feed back supply circuit over the back point thereof. Under this condition, battery FB transmits a pulse of feed back energy over the line conductors to the code following relay FR at the opposite or master end of the circuit.

At the end of the release period of the feed back coder relay FC, contacts 37 thereof drop out and thus terminate the feed back pulse. The apparatus at the feed back end of the line circuit is now conditioned for reception of and response to the succeeding pulse of master code energy. This pulse is supplied when the contacts 75a of the transmitter CT15 at the master end of the circuit return to their uppermost position.

When that happens the just described cycle of two direction coded line circuit operation starts to repeat itself and in the manner just outlined the "master" and the "feed back" circuit facilities operate over the line circuit conductors simultaneously and without interfering with each other.

The four-code group of line circuits 12-13 and 14-15 of Fig. 1 will finally be considered. Both of these circuits are identified with the length of track which extends between locations III and IV and which is spanned by the passing siding PS.

Each operates on the "coded feed back" prin-

ciple which has just been explained in connection with the two-code circuits of the Fig. 1 system. Thus each includes: master and feed back batteries MB and FB at opposite ends of the line circuit; oppositely located master and feed back code following relays MR and FR which respectively are operated by energy received over the line conductors from the master and feed back batteries; a feed back coder relay FC which controls the connection of the feed back battery with the circuit conductors; and code transmitter means CT which control the connection of the master battery with the circuit conductors and also control the connection of these conductors with the feed back energized relay FR.

In the case of each of the four-code line circuits 12-13 and 14-15, the above-mentioned code transmitter means include not only the 75 pulse per minute code transmitter 75CT but also 20 a companion transmitting device 180CT the contacts of which operate at the higher rate of 180 cycles per minute. Selection between these two transmitters is made by contacts 51 of track relay TR (for section II-III) in the case of circuit 12-13 and by contacts 52 of a relay H75 (at location III-later to be described) in the case of line circuit 14-15.

In the both instances these code selecting means are located at the "master" end of the four-code line circuits. When, as shown in the drawing, these selector contacts (51 and 52) are picked up the high speed code transmitter 180CT performs the master code producing function for the line circuit while when the selector contacts are released the companion or slow speed transmitter 75CT is similarly brought into active use.

Since only the selected transmitter need be kept in operation the driving circuits for the two devices 180CT and 75CT at location III are selectively energized over the front and back points of a contact 53 of the track relay TR for section II-III. When this contact is picked up, transmitter 180CT is brought into action and the transmitter 75CT is maintained inactive. When, however, the contact is released the reversed relation applies and only transmitter 75CT is maintained in operation. This same transmitter also comes into action when contact 34 of a relay HW (later to be described) is released.

Also controlled by the same contact 53 of the track relay TR at location III is the energizing circuit for the before-mentioned repeater relay TP. As long as contact 53 is picked up this repeater relay receives energy over conductor 54 and also holds all of its contacts picked up. When, however, the track relay for section II-III releases, contact 53 breaks the energizing circuit for the repeater relay and allows that relay then to release its contacts.

Looking now at the opposite or "feed back" ends of the two four-code line circuits 12-13 and 14-15, it will be seen that the added requirements of a second code following speed on the part of the master relay MR have occasioned supplemental features in connection with the snubbing circuit for the feed back coder relay FC. These take the form of a second resistor section 56 which at times is substituted for section 36 in the relay snubbing circuit.

When the master and coder relays MR and FC are being operated at the 75 pulse per minute code rate, a contact 57 of a code distinguishing relay (H180 in the case of circuit 12-13 and D180 in the case of circuit 14-15) later to be described is released and then serves to connect

the long delay resistor section 36 in snubbing relation with the winding of coder relay FC. This causes the relay to have a period of release delay of the previously described order indicated at *k* in Fig. 4.

When, however, the master and feed back relays MR and FC are being operated at the 180 energy pulse per minute code rate, the code detecting relay contact 57 is picked up and it then transfers the snubbing connection to the second resistor section 56. This section is so electrically dimensioned as to produce a shorter period of release delay on the part of the feed back coder relay FC. In practice this shorter period will have the order designated at *x* in Fig. 4 and in all instances will be somewhat less than the length of the "off" periods for the 180 pulse per minute master code.

Normally, both of the four-code line circuits 12-13 and 14-15 are maintained intact and under that condition each operates on the "coded feed back" principle already explained in connection with the two-code line circuits of Fig. 1. At times, however, each of these circuits is interrupted for the purpose of effecting certain signal control functions later to be described. In the case of circuit 12-13 this interruption is effected by contacts 58, 59 and 60 of the track relays TR at locations III and IV; in the case of line circuit 14-15 it is effected by contacts 61 of a relay HE (later to be described) at location IV.

Under the normal intact condition, each of the four-code line circuits 12-13 and 14-15 operates in the manner basically the same as that already explained for the two-code line circuits of the Fig. 1 system. The same "coded feed back" principle applies and because of the basic identity no detailed description thereof will here be repeated.

For the present it will suffice to say that the selected transmitter 15CT or 180CT repeatedly connects the line circuit conductors first with the master battery MB and then with the feed back receiving relay FR. Each of the connections first stated constitutes an "on" period in one of the "master" codes of Fig. 4 and causes a pulse of energy to be transmitted over the line conductors to the master code following relay MR at the opposite end of the circuit. In responding in conventional manner that relay causes the associated coder relay FC to connect the feed back battery FB with the line circuit conductors during each "off" period of the master code. Each of the resulting pulses of feed back energy is transmitted over the line conductors to the code following relay FR at the opposite or master end of the circuit. That relay responds in conventional manner and effects the signal control functions later to be described.

If the transmitter 180CT is in action the rate of code following speed on the part of both of relays MR and FR will be 180 times per minute and, under that condition, contact 57 of the associated code detecting relay will connect snubbing resistor 56 across the feed back coder relay FC. This will shorten the period of release delay to the order indicated at *x* in Fig. 4, and thus assure that each pulse of feed back energy will not overlap adjacent pulses of the master code energy.

In the event that the transmitter 15CT is actively functioning, then the rate of code following speed on the part of both of the relays MR and FR will have the slower value of 75 times per minute. Under that condition contact 57 con-

nects resistor 36 across the feed back coder FC and thus prolongs the period of release delay to the order indicated at *k* in Fig. 4. Under all conditions, therefore, the pulses of feed back energy approach the maximum permissible length.

This and the other unique features of the four-code line circuits 12-13 and 14-15 of Fig. 1 are illustrated in somewhat simplified manner in Fig. 3. In that view I have represented the several elements of line circuit 12-13 which cooperate in the "coded feed back" form of operation.

Control of system signals

Description now having been given of the steady energy track circuits for the single track stretch of Figs. 1a-c and the several coded line circuits (single-code, two-code and four-code) that cooperate therewith, attention will next be directed to the facilities through which these track and line circuits control the wayside signals SE and SW in the opposing overlap manner of Fig. 2. Inasmuch as these facilities differ somewhat at different locations, the control means for each of the system signals will be described individually.

Referring first to location I of Fig. 1a and the westbound signal SW thereat, the indication which this "distant" device displays is selected by the master relay MR of the previously described line circuit 5-6 and through the medium of a code detecting relay DW. This relay carries a contact 29 which is included in the energizing circuit for the lamps G and Y of the controlled signal. These circuits, in turn, derive lighting current from a local supply source designated by the terminals "plus" and "minus."

Relay DW receives its energizing current through a transformer 25 and from a direct current source that again is designated by the terminals "plus" and "minus." This relay is a slow releasing device and it is controlled by the line relay MR in such manner as to be maintained picked up as long as that line relay follows code and to release when the line relay ceases to follow code.

The represented association of relay DW with the transformer 25 and the line relay MR is the same as that disclosed and claimed by copending application Serial No. 210,744, filed May 28, 1939, by Frank H. Nicholson et al. In that association the transformer 25 receives exciting current over a pole changing contact 26 of the line relay and the code detecting device receives pick-up energy from the transformer over a rectifying contact 27 of the line relay.

In determining the aspect which the controlled signal SW displays, this code detecting relay DW makes use of the previously named contact 29. As long as the associated line relay MR is following code and relay DW is picked up, lamp G is lighted over the front point of contact 29. Under this condition the signal shows "clear." When, however, the line relay ceases to follow code and device DW is released, lamp Y is lighted over the back point of contact 29 and the signal then shows "approach."

Considering next the eastbound signal SE at location I, the indication which this "home" device displays is selected by the master relay MR of the previously described line circuit 7-8 through the medium of a code detecting relay HE. This relay carries a contact 34 which is included in the lighting circuits for the lamps G and R of the controlled signal.

This code detecting relay HE is controlled by

the associated line relay MR through facilities which are identical with those just described for relay DW. These facilities keep the code detecting relay picked up as long as the line relay follows code and allow it to release when the line relay ceases to follow code. Under the former condition, lamp G of signal SEI is lighted over the front point of contact 34 and the signal then shows "clear"; under the latter, lamp R is lighted over the back point of contact 34 and the signal then shows "stop."

Referring now to location II of Fig. 1a, it will be seen that the westbound "home" and the eastbound "distant" signals SWII and SEII thereat respectively are controlled through the medium of code detecting relays HW and DE which, in turn, are respectively governed by feed back and master line relays FR and MR of line circuits 7-8 and 9-10. Each of these code detecting relays is associated with a transformer 25 and the controlling line relay in the same manner as that disclosed and claimed by the previously mentioned Frank H. Nicholson et al. application Serial No. 210,744.

As long, therefore, as relay FR at location II is following code detecting relay HW is held picked up to light (over the front point of contact 34) the "clear" lamp G of signal SWII; when, however, relay FR ceases to follow code, detecting relay HW releases and "stop" lamp R of the named signal then is lighted over the back point of contact 34.

Similarly, as long as relay MR at location II follows code, detecting relay DE is held picked up to light (over the front point of contact 29) the "clear" lamp G of signal SEII; when, however, relay MR ceases to receive coded energy from line circuit 9-10, detecting relay DE releases and "approach" lamp Y of signal SWII then is lighted over back contact 29.

At location III of Fig. 1a the "home" westbound signal SWIII is controlled through a code detecting relay HW and by a feed back line relay FR which, as in the case of relay FR at location II, also receives operating energy from line circuit 7-8. As long as this feed back energy continues to be received over the back points of contacts 75a of transmitter 75CT, this relay HW is held picked up and "clear" lamp G of signal SWIII is lighted over front contact 34; when, however, relay FR ceases to follow code, relay HW releases and "stop" lamp R of signal SWIII then is lighted over back contact 34.

Referring to signal SEIII at location III, it will be seen that this signal includes a "home" unit R-G and a "distant" unit Y-G. These two units respectively are controlled through relays HE and DE at the signal location and by the feed back code following relays FR and FRI of line circuits 12-13 and 14-15.

Each of the just named code detecting relays HE and DE has response characteristics which are the same as those already described in connection with similarly identified devices at locations I and II. In the case of the "home" unit R-G of signal SEIII the "clear" lamp G is lighted as long as the line relay FR continues to follow feed back code from line circuit 12-13 of either the 75 or the 180 pulse per minute rate, while the "stop" lamp R is lighted when relay FR ceases to follow code.

Likewise in the case of the "distant" unit Y-G of signal SEIII the "clear" lamp G is lighted as long as relay FRI continues to receive from line circuit 14-15 feed back code of either the 75

or the 180 pulse per minute variety, while the "approach" lamp Y of the same signal is lighted when line relay FRI ceases to follow code.

At location IV of Fig. 1b, the eastbound "home" signal SEIV is controlled through code detecting relay HE and by the feed back relay FR of line circuit 16-17. As long as this relay FR continues to respond to feed back code received from the just named line circuit, detecting device HE is picked up and "clear" lamp G of the controlled signal is lighted over front contact 34; when, however, relay FR ceases to follow code, device HE releases and lights "stop" lamp R of signal SEIV over back contact 34.

As in the case of eastbound signal SEIII at location III, the westbound signal SWIV at location IV includes a "home" unit G-R and a "distant" unit G-Y. The former is controlled through a code distinguishing relay H180 and by the master relay MR of line circuit 12-13, while the latter is controlled through a second code distinguishing relay D180 and by the master relay MRI of line circuit 14-15.

Each of the just named code distinguishing relays receives its pick-up energy from a decoding transformer DT which, in turn, is excited from a local direct current source over a circuit that is controlled by a pole changing contact 26 of the associated code following line relay MR. The secondary winding of this decoding transformer is connected in energy supplying relation with the code distinguishing relay through a resonant unit 180DU which permits energy of pick-up intensity to be transmitted to the relay only when the master line relay MR responds to operating energy of the 180 pulse per minute code.

Hence, the elements just named cooperate to cause the code distinguishing relay H180 to pick up when the master relay MR of line circuit 12-13 is operating at the 180 code rate and to release at all other times. Likewise, they cause the code distinguishing relay D180 to pick up only when master relay MRI is responding to 180 pulse per minute code received from line circuit 14-15 and to release at all other times.

In determining the aspect which is displayed by the "home" and "distant" units of the controlled wayside signal SWIV, the above described code distinguishing relays make use of contacts 34 and 29. When contact 34 is picked up "clear" lamp G of the "home" unit then is lighted, while when the same contact is released the "stop" lamp R of the same unit is lighted. Similarly, when contact 29 is picked up the "clear" lamp G of the "distant" unit is lighted, while when contact 29 is released the "approach" lamp Y of the same unit is lighted.

Referring to location V, the "distant" westbound signal SWV thereat is controlled through a code detecting relay DE and by the code following relay MR of line circuit 18-19. As long as this line relay follows code the detecting device is picked up and front contact 29 then sets up a lighting circuit for the "clear" lamp G of the controlled signal. When, however, relay MR ceases to follow code then relay DE releases and back contact 29 sets up a lighting circuit for the "approach" lamp Y of the signal.

In order for either of these circuits to be completed it is necessary that a contact 64 of an approach lighting relay AR be released. This approach relay is installed at the location of the controlled signal in the manner shown and it derives pick-up current from a full-wave rectifier 65 that is serially connected in one of the con-

ductors of line circuit 16-17. The relay has slow releasing characteristics and as long as the named line circuit transmits the coded energy of either the "master" or the "feed back" variety the relay is held picked up to keep the associated wayside signal SWV dark.

In the event, however, that the line circuit 16-17 becomes interrupted at any point between its end locations IV and VII then relay AR at location V becomes released and connects the lighting circuits of signal SWV with their energizing source. Under that condition, the signal responds in the manner explained to the position of contact 29 of code detecting relay DE.

At location VI the "home" eastbound signal SEVI is provided with comparable control facilities. These include an indication selecting relay HE governed through transformer 25 by code following relay MR of line circuit 20-21 and an approach relay AR which in all respects is a 20 duplicate of the correspondingly identified device just described at location V.

As long as line circuit 16-17 continues to transmit coded energy this approach relay is picked up and the associated wayside signal SEVI then remains inactive or dark. When, however, the just named line circuit is interrupted relay AR becomes deenergized and the back point of contact 64 then connects the lighting circuits of the associated signal with their energizing source.

Under that condition, the signal responds to the presence or absence of code following action on the part of relay MR of line circuit 20-21. When this relay is following code, contact 34 of device HE completes the lighting circuit for "clear" lamp G of the signal, while when relay MR is not following code the back point of contact 34 completes the "stop" or red lamp circuit for signal SEVI.

In the case of "home" westbound signal SWVII at location VII a corresponding scheme of control is provided. The facilities thereof include an indication selecting relay HW which distinguishes the presence or absence of code following operation on the part of the master relay MR of line circuit 16-17 and an approach relay AR which distinguishes the presence or absence of coded energy in line circuit 20-21.

As long as energy is being transmitted by this line circuit 20-21, relay AR is picked up and contact 64 thereof keeps the lighting circuits of signal SWVII disconnected from their energizing source. In the event, however, that the just named line circuit is interrupted at any point throughout its length, relay AR at location VII releases and conditions the signal SWVII for response to the position of contact 34 of relay HW at the same location. Under that condition the signal shows "clear" when relay MR of line circuit 16-17 is following code and "stop" when that master line device ceases to follow code.

Referring finally to the "distant" eastbound signal SEVIII at location VIII, the control facilities for this device also correspond to those which have just been explained. They include an indication selecting relay DE which detects the presence of code following operation on the part of relay MR of line circuit 22-23 and an approach relay AR which maintains the signal inactive as long as line circuit 20-21 continues to transmit coded energy and which connects the selected signal lamp with its lighting source when and only when the transmission of that energy is discontinued. Under the latter condition the

signal shows "clear" when the relay MR of circuit 22-23 is following code and "approach" when the just named relay ceases to follow code.

Operation of complete system of Figs. 1a-c

The apparatus and circuits which are utilized in the coded line circuit signal control system of Figs. 1a-c now having been described, the manner in which this system operates to provide both directional and following protection for trains which move through the stretch of single track 1-2 will now be explained. As an aid to this explanation, further reference will be had to the control limit and code diagrams of Figs. 2 and 4.

In explaining this operation, typical moves of eastbound trains through the stretch will first be traced and the following protection which is incident thereto will be pointed out; representative moves of westbound trains through the stretch will then be traced for the purpose of explaining the following protection which is incident thereto; and finally opposing moves will be considered in the light of the directional protection which the overlap signal control scheme provides.

Under the represented vacant conditions of the track stretch of Figs. 1a-c, all of the track relays TR are picked up; all of the coded line circuits in the system are transmitting energy in the manner previously explained; all of the line relays MR and FR are following code; all of the indication selecting relays DW, HW, DE, HE, D¹⁸⁰ and H¹⁸⁰ are picked up; all of the approach relays AR also are picked up; and each of the wayside signals SE and SW is either displaying or set up to display the "clear" indication.

In considering the following protection which the system provides, it will be helpful to note that the track and line circuits that are identified with the various sections of track in the protected stretch form part of two systems which respectively control in the customary automatic block manner the eastbound signals SE during conditions of eastbound moves and the westbound signals SW during conditions of westbound moves. In the form illustratively represented, each of these automatic block systems is of the two indication variety. As the description proceeds, however, it will become apparent that in providing the following protection now about to be explained both the eastbound signals SE and the westbound signals SW may readily be controlled to more than the two indications which are here disclosed.

As an eastbound train enters the track stretch from the left and proceeds therethrough the following actions take place. In successively approaching each of locations I, II, III, IV, VI and VIII the train gets a "clear" indication from the eastbound signal SE which is there installed. In the case of each of the approach lighting signals SEVI and SEVIII this "clear" display results from a release of the relay AR at the signal location which was respectively produced when the train approached these two signals and caused track relays TR to interrupt line circuits 16-17 and 20-21.

As the train advances past location I and releases the track relay TR at location II, contacts 44 of that relay break line circuit 7-8 and disconnect the relay MR at location I from its energizing source. The associated relay HE now releases and puts signal SEI at "stop". This "stop"

display continues until the train has cleared location II.

In entering section II-III the train releases relay TR at location III and thus causes the repeater device TP to drop contacts 36. That action deenergizes relay MR at location II and by releasing the associated relay DE puts eastbound signal SEII at "approach." This "approach" display continues until the train clears location III. When that happens, relay TR for section II-III again picks up and by restoring the continuity of line circuits 7-8 and 9-10 causes both of the wayside signals SEI and SEII to return to "clear."

In entering signal block III-IV, the eastbound train causes one of the associated track relays TR to break line circuit 12-13 and thus it de-energizes feed back relay FR at location III. This action drops the associated relay HE and puts at "stop" the "home" unit of eastbound signal SEIII. This aspect continues until the train clears location V and thus allows both of the track relays TR at location IV to pick up and restore the supply of feed back energy to relay FR at location III. Upon such restoration, the associated relay HE picks up and restores the "home" unit of signal SEIII to "clear."

In advancing into section IV-V the train releases the track relay TR for that section and breaks line circuit 16-17 at contact 39. This break deenergizes relay FR at location IV and by dropping relay HE puts eastbound signal SEIV at "stop". At the same time, contacts 61 of relay HE cut off the supply of feed back energy to relay FR at location III and by dropping relay DE put the "distant" unit of signal SEIII at "approach." This aspect also continues until the train clears location V.

As the train enters section V-VI and approaches signal SEVI, one or the other of relays TR for the section keep line circuit 16-17 interrupted and thereby release relay AR at location VI. This causes signal SEVI to display the "clear" indication for which it is set up by the associated relay HE.

In entering section VI-VII the eastbound train releases relay TR for that section and breaks (at contacts 47) the line circuit 20-21. This break deenergizes relay MR and by releasing relay HE causes signal SEVI to show "stop." Once established, this "stop" aspect continues until the train clears location VIII.

In approaching that location, the train brought signal SEVIII into action as the result of the before explained interruption of line circuit 20-21 at the contacts of track relays TR and the resulting release of relay AR at location VIII. In consequence, signal SEVIII displays the "clear" indication which relay DE sets up. As the train passes location VIII, track relay means (not shown in Fig. 1c) interrupt line circuit 22-23 and by deenergizing relay MR and releasing relay DE cause eastbound signal SEVIII to show "approach."

From the foregoing it will be seen that during eastbound train movements through the protected stretch the just explained scheme of automatic block signaling provides the usual following protection which maintains a safe spacing between successive eastbound trains. That is, as long as an advance train occupies (and shunts the rails of) a signal block of the system track, the wayside signal SE at the west (eastbound entrance) end of that block is conditioned to show "stop" and succeeding signals SE to the

west are conditioned to show either "approach" or "clear." As, moreover, the train moves eastwardly along the rails the above stated combination of signal indications continues to be maintained behind it and in this way following protection for eastbound moves is at all times provided.

Westbound train moves through the protected stretch of Figs. 1a-c will now be considered. Each 10 westbound train which passes along the track automatically sets up for itself following protection of the character just described in connection with eastbound moves. This following protection results from the actions which will now 15 be described in tracing the passage of a westbound train through the stretch.

Under vacant conditions of the protected stretch, the several westbound signals SW therealong have the condition represented in the composite diagram of Figs. 1a-c. Each either displays or is set up to display the "clear" indication as a result of the associated track relays TR being picked up and the associated line circuits transmitting coded energy in the normal manner.

As, now, a westbound train enters the stretch from the right and comes into section VIII-VII it causes westbound signal SWVII to light and display the "clear" indication set up by the associated relay HW. The mentioned lighting is produced by the release of relay AR at location VII which accompanies the interruption of line circuit 20-21 by one of the relays TR.

As the westbound train moves on into block 35 VII-V, relay TR at location VI interrupts line circuit 16-17 and by deenergizing relay MR at location VII and releasing the associated relay HW puts signal SWVII at "stop." Once set up, this aspect continues until the train has cleared 40 location V.

In approaching location V, the westbound train gets from signal SWV the "clear" indication which the associated relay DE sets up and which the now released relay AR makes visible. This 45 release of the approach relay results, of course, from an interruption of the line circuit 16-17 at the contacts of one of the track relays TR.

As the train enters section V-IV, it causes relay TR at location IV to interrupt line circuit 50 18-19. This action deenergizes relay MR at location V and by releasing relay DE puts westbound signal SWV at "approach." This aspect continues until the train has cleared location III, at which time the signal SWV is returned 55 to the "clear" aspect set-up.

In approaching location IV, the westbound train gets the "clear" indication from signal SWIV as a result of both of the associated relays D180 and H180 being held picked up under the action of "Master 180" code energy being transmitted eastwardly over line circuits 12-13 and 60 14-15.

As the westbound train moves into block IV-III, the "home" unit G-R of the just named signal shows "stop" as a result of relay TR at 65 location VI interrupting line circuit 12-13 and causing relay H180 to release. This "stop" aspect continues until the train has cleared location II.

In accepting the "clear" indication from signal SWIII the train moves on into section III-II. At location III this releases relays TR and TP and by deenergizing relay FR of line circuit 7-8 drops out the associated relay HW and thus 70 75 puts westbound signal SWIII at "stop." That

action is accompanied by a release of contacts 52 of relay HW and a substitution in each of the line circuits 12-13 and 14-15 of code transmitter 15CT for the normally active transmitter 180CT.

At location IV, relay D180 now releases (due to the slowed down code following action of relay MRI) and thus puts the "distant" unit of signal SWIV at "approach." At the same time, relay H180 also continues released and holds the "home" unit of the same signal at "stop."

In accepting the "clear" indication from signal SWII the westbound train advances into section II-I. This action releases track relay TR at location II and by breaking line circuit 7-8 at contacts 44 deenergizes feed back relay FR at the same location. The associated relay HW now releases and puts signal SWII at "stop."

As the train clears location II, relay TR picks up and restores the coding of line circuit 12-13 to transmitter 180CT. At location IV, this causes the pick-up of relay H180 and the restoration of the "distant" unit G-Y of signal SWIV to its "clear" indication.

In accepting the "clear" indication from signal SWI, the westbound train advances west of location I. In so doing, it causes (through facilities not shown in Fig. 1a) the interruption of line circuit 5-6 and by deenergizing relay MR and releasing relay DW puts signal SWI at "approach."

As the train clears location I, relay TR at location II restores (at contacts 44) the continuity of line circuit 7-8 and thus causes relay FR at location III again to receive coded feed back energy from that line circuit. In consequence, the associated relay HW again picks up and restores westbound signal SWIII to its "clear" indication.

At the same time, contacts 52 of the last named relay cause code transmitter 180CT again to become active in line circuit 14-15. At location IV, master relay MRI follows the 180 code and picks up relay D180, thereby restoring the "distant" unit G-Y of signal SWIV to its "clear" indication.

From the foregoing, it will be seen that the just described westbound scheme of automatic block signaling provides the usual following protection for all westbound train moves. That is, as long as a westbound train occupies (and shunts the rails of) a section of the system track, the wayside signal SW at the east (westbound entrance) end of that section continues to show "stop" and the next signal SW to the east is continuously conditioned to show either "approach" or "clear." As, moreover, the train moves westwardly along the rails, the above stated combination of signal indications continues to be maintained behind it and in this way following protection for westbound trains is at all times provided.

Overlap protection during opposing moves

In addition to providing the protection which has just been described for following movements of both eastbound and westbound trains, the wayside signals SE and SW along the track stretch of Fig. 1 further permit opposing trains to move through the signaled stretch without the hazard of entering the same signal block at the same time and colliding head on.

As earlier stated, this opposing or directional protection is effected by carrying the control circuits for preselected "home" signals beyond the

next signals in advance, which govern in the same direction, at least full braking distance and making the continuity of these circuits dependent upon the condition of the track sections ahead of those advance signals. As previously pointed out, moreover, one preferred form of such "overlap" signal control is shown in Fig. 2.

In the explanation now about to be given, reference will be made not only to the composite diagram of Fig. 1 but also to this control limit diagram of Fig. 2. From the latter it will be seen that the "home" unit R-G of eastbound signal SEIII has an advance control range which extends not only to the next "home" signal SEIV 10 ahead but also for the length of section IV-V; that eastbound signal SEIV has an advance control range which extends not only to the next "home" signal SEVI ahead but also for the further combined lengths of sections VI-VII and 15 and VII-VIIa; that the westbound "home" signal SWVII has an advance control range which extends beyond the next signal SWV in advance for the distance of section V-IV; that the "home" unit R-G of westbound signal SWIV 20 has an advance control range extending beyond the next signal SWIII for the length of section III-II; and so on.

Assume now that an eastbound train is approaching location III from the west at the same time that a westbound train is approaching location V from the east. Obviously, one of the two trains must be diverted to the passing siding PS while the other proceeds therewith along the main track 1-2 and the embodiment of my invention 25 herein disclosed provides full protection during such a passing maneuver.

As long as the eastbound train stays to the west of location III and the westbound train stays to the east of location V, each of these trains gets a "permissive" indication from the signal (SEIII and SWV) that is immediately ahead. In the case of the eastbound signal SEIII, this indication is "clear," it is displayed by the unit Y-G, and it results from the transmission over line circuit 14-15 of "feed back" energy to code following relay FRI at location III. In the case of westbound signal SWV, the permissive indication is "approach" and results from line circuit 18-19 being interrupted at contacts 33 of code distinguishing relay H180 of the line circuit 12-13.

This "approach" indication warns the westbound train that the track ahead is occupied by an opposing eastbound train and requires that the westbound train proceed with caution. Meanwhile, the eastbound train is free to accept the "clear" indication at location III and to proceed therewith into block III-IV.

It will be assumed that under the authority of a train order the eastbound train is switched to passing siding PS and in the usual manner is entirely removed from the main track 1-2. During all of this time some portion of the eastbound train is shunting section III-IIIa and thus causing line circuit 12-13 to be interrupted at contacts 53 of relay TR. This interruption continues the "stop" indication on the part of the "home" unit G-R of the westbound signal SW at location IV. As, therefore, the westbound train approaches that signal it is warned not to enter block IV-III.

Meanwhile, the eastbound train has completely left the main track 1-2 and is all on the passing siding PS. With the restoration of the switches W to the normal "through traffic" posi-

tion, the rails throughout the entire block IV-III are unshunted and both of the associated track relays TR pick up. This action restores line circuit 12-13 to its completed condition and as a result of the transmission of "Master 180" code eastwardly thereover, code distinguishing relay H180 again picks up and restores the "clear" aspect to westbound signal SWIV.

Accepting this aspect, the westbound train enters the block IV-III and proceeds therethrough under the usual vacant track conditions. This having taken place, the eastbound train is advanced from the passing siding PS back on to the main track 1-2. It accepts the "clear" indication from eastbound signal SEIV and proceeds therewith, also under the usual vacant track conditions.

In the manner just stated, therefore, opposing trains are permitted to pass one another under full automatic protection against head-on collision. While the maneuver just described requires that the eastbound train take to the passing siding, a passing of the two trains may also be accomplished by keeping the eastbound train on the main track and having the westbound train take to the siding.

Such a modified passing maneuver will now be described. First assume that the eastbound train is approaching location II at a time when a westbound train is approaching location IV. Under this set of circumstances each of the two trains receives the "clear" indication from the wayside signal (SEII and SWIV) which is immediately thereahead.

In the case of the eastbound signal SEII, this "clear" indication results from line circuit 9-10 being kept intact and transmitting coded energy in the normal manner, while in the case of the "home" and the "distant" units G-R and G-Y of the westbound signal SWIV it similarly results from line circuits 12-13 and 14-15 transmitting "Master 180" code energy in the normal vacant track manner.

At location III, the just stated indications are accompanied by the display of "stop" on the part of eastbound signal SEIII. This "stop" aspect is given by the "home" unit R-G and results from the action of relay TR for section V-IV in cutting off (at now released contact 60) the transmission of "feed back" energy over line circuit 12-13 to the code following relay FR at location III.

Accepting the "clear" indication at location IV, the westbound train proceeds therewith and enters block IV-III. Under train orders, it takes to the passing siding PS preparatory to clearing the main track 1-2 for a later passage thereover of the eastbound train. Meanwhile, some portion of the westbound train continues to shunt section IV-IIIa and by interrupting the line circuit 12-13 at contacts 59 causes eastbound signal SEIII to continue to show "stop."

Once the westbound train has completely left the main track and the switches W are restored to the normal or "through traffic" position, the rails of block IV-III are unshunted and both of the line circuits 12-13 and 14-15 are restored to their normal or 180 code transmitting position. In consequence, both of the units of eastbound signal SEIII once more show "clear."

Before that happens, however, the shunting of the rails of section IV-IIIa by the westbound train put the eastbound signal SEII at "approach." This resulted from the before described release of relay HE at location III and

the consequent interruption at contacts 31 thereof of line circuit 9-10. That "approach" indication at location II continued only as long as the westbound train was entering the passing siding PS. With the later shunt removal from the rails of block IV-III, contacts 31 of relay HE at location III again restored line circuit 9-10 to its operative condition and thus caused signal SEIII again to show "clear."

Accepting this "clear" indication, the eastbound train now proceeds into section II-III and gets the before described "clear" indication from signal SEIII. Accepting that indication, it proceeds into and through block III-IV in the usual vacant track manner.

Once the eastbound train has cleared location IV, the westbound train is free to advance from the passing siding PS back on to the main track 1-2 and out of block IV-III in the usual vacant track manner.

In the further manner stated, therefore, it will be seen that my improved overlap signaling scheme permits opposing trains to pass one another under full automatic protection against head-on collision.

It is believed that the opposing move analysis thus far given will be sufficient to make clear how all of the line circuit governed signals of Fig. 1 are controlled in the overlap manner which is represented by the control limit diagram of Fig. 2. For this reason, no further description of the here disclosed control facilities will be attempted.

When organized in the improved manner of my invention these facilities offer many advantages which are both desirable and practical. For example, they protect against improper signal operation due to an accidental crossing or breaking of the line circuit conductors. By interrupting transmission of the coded line circuit energy either of those actions causes the controlled signal to display its most restrictive or "stop" aspect and because of that characteristic the signaling system as a whole has a high inherent factor of safety.

Summary

While the improvements of my invention have been disclosed in connection with an opposing overlap scheme of automatic signaling for two direction running track, it will be apparent that the disclosed type of control is not necessarily confined to the overlap application but may also be used with other forms of single track signaling, such as those which involve the absolute permissive block (APB) scheme of signal control. Likewise, while the several "coded feed back" line circuit combinations in the system have been shown as receiving operating energy from the direct current sources MB and FB, it will further be apparent that these same line circuits (see the simplified showing of Fig. 3) may readily be modified to operate on alternating current. Still further, while the controlled signals are shown as being of the color light type, it is equally apparent that further classes of signals may also be controlled by this general scheme of line circuit organization.

From the foregoing, accordingly, it will be seen that I have made highly practical improvements in line wire signaling systems for stretches of railway track over which traffic may move in either direction.

In particular, I have reduced the number of control conductors which line wire systems of railway signaling require; I have utilized a single

pair of line wires to control signals that govern traffic in either direction; I have provided new and improved facilities for overlapping the track circuit control limits of the system signals; I have protected against improper signal operation due to an accidental crossing or breaking of the system line wires; I have made a new and novel application of the "coded feed back" principle of Frank. H. Nicholson Patent No. 2,021,944; and I have provided improved apparatus for use in line and other circuits of the "coded feed back" type.

Although I have herein shown and described only one form of signaling apparatus embodying my invention, it is understood that various changes and modifications may be made therein within the scope of the appended claims without departing from the spirit and scope of my invention.

Having thus described my invention, what I claim is:

1. In combination, a control circuit which includes a pair of conductors, means at a given end of said circuit for supplying said conductors with master code energy in the form of "on" period pulses that are separated by "off" period intervals and that recur at a high speed rate at times and at a low speed rate at other times, a code following master relay at the opposite end of said circuit which responds only to the pulses of said master code energy that are there received, a similarly located source of feed back energy, a coder relay which is picked up by said master relay during each "on" period of said received master code and which releases during each succeeding "off" period of that code, means including a back contact of said master relay and a front contact of said coder relay for connecting said feed back source with said circuit conductors at the beginning of each of said "off" code periods whereby to supply said conductors with a pulse of feed back energy during each of those "off" periods, means effective when said received master code is of said high speed variety for delaying each release of said coder relay for a time just less than the "off" period length of that high speed code whereby each of said feed back pulses then is prolonged for substantially its full permissible duration, means effective when said received master code is of said low speed variety for delaying each release of said coder relay for a time just less than the "off" period length of that low speed code whereby each of said feed back pulses then also is prolonged for substantially its full permissible duration, and traffic governing apparatus controlled by the said feed back energy which said conductors transmit to said given end of the control circuit.

2. In combination, a control circuit which includes a pair of conductors, means at a given end of said circuit for supplying said conductors with master code energy in the form of "on" period pulses that are separated by "off" period intervals and that recur at a high speed rate at times and at a low speed rate at other times, a code following master relay at the opposite end of said circuit which responds only to the pulses of said master code energy that are there received, a coder relay which is picked up by said master relay during each "on" period of said received master code and which releases during each succeeding "off" period of that code, means effective when said received code is of said high speed variety for delaying each release of said coder relay for a time less than the "off" period

length of that high speed code, means effective when said received code is of said low speed variety for delaying each release of said coder relay for a time longer than that just named but less than the "off" period length of the low speed code, a source of feed back energy at said opposite circuit end, a connection including a back contact of said master relay and a front contact of said coder relay over which said feed back source supplies feed back energy to said control circuit conductors during each "off" period of whichever of said two master codes said master relay receives, and traffic governing apparatus controlled by the said feed back energy which said conductors transmit to said given end of the control circuit.

3. In a system of railway signaling, a control circuit which includes a pair of conductors, means at a given end of said circuit for supplying said conductors with master code energy in the form of "on" period pulses that are separated by "off" period intervals and that recur at a high speed rate at times and at a low speed rate at other times, a code following master relay at the opposite end of said circuit which is energized and picked up by each pulse of said master code energy that is there received, a coder relay which is picked up by said master relay during each "on" period of said received master code and which releases during each succeeding "off" period of that code, snubbing means for said coder relay which include a first element that produces a short release delay less than the "off" period length of said high speed code and a second element that produces a longer delay less than the "off" period length of said low speed code, means governed by said master relay for rendering said short delay element effective when the master relay is responding to said high speed code and for rendering said longer delay element effective when the master relay is responding to said low speed code, a source of feed back energy at said opposite circuit end, a connection including a back contact of said master relay and a front contact of said coder relay over which said feed back source supplies feed back energy to said control circuit conductors during each "off" period of whichever of said two master codes said master relay receives, means for rendering said master relay unresponsive to the said energy which said feed back source supplies, and traffic governing apparatus controlled by the said feed back energy which said conductors transmit to said given end of the control circuit.

4. In combination, a section of railway track, a control circuit which is coextensive with said section and which includes a pair of line conductors, means at a given end of said circuit for supplying said conductors with master code energy in the form of "on" period pulses that are separated by "off" period intervals and that recur either at a high speed rate or at a low speed rate, a code following master relay at the opposite end of said circuit which responds only to the pulses of said master code energy that are there received, a coder relay which is picked up by said master relay during each "on" period of said received master code and which releases during each succeeding "off" period of that code, snubbing means effective when said received master code is of said high speed variety for delaying each release of said coder relay for a time less than the "off" period length of that high speed code, other snubbing means effective when said received master code is of said low speed

variety for then delaying each release of said coder relay for a time longer than that just named but less than the "off" period length of the low speed code, a source of feed back energy at said opposite circuit end, a connection including a back contact of said master relay and a front contact of said coder relay over which said feed back source supplies feed back energy to said line conductors during each "off" period of whichever of said two master codes said master relay receives, means responsive to the presence of a train in said section for causing said line conductors to discontinue energy transmission between said two circuit ends, traffic governing apparatus controlled by the said master code energy which is received at the said opposite circuit end, and other traffic governing apparatus controlled by the said feed back energy which is received at said given circuit end.

5. In combination, a stretch of railway track which is arranged into successive track sections and over which traffic may pass in either direction, a signal block length of said track which embraces at least one of said sections, first and second signals respectively identified with opposing ends of said block and respectively arranged to govern the entry thereinto of first direction trains and of second direction trains, a control circuit that includes a pair of line conductors which are coextensive with said block, means at the first signal end of said control circuit for supplying said conductors with master code energy in the form of recurring pulses that are separated by "off" period intervals, means at the second signal end of said control circuit which receive said master code pulses and which cause said second signal to display its "clear" aspect as long as said reception continues and a restrictive aspect when that reception is interrupted, similarly located means which further supply said circuit conductors with pulses of feed back energy that recur in step with the "off" period intervals of said received master code, means at the first signal end of said control circuit which receive said feed back pulses and which cause said first signal to display its "clear" aspect as long as said reception continues and a restrictive aspect when that reception is interrupted, means effective whenever a train is in said signal block for interrupting said line circuit and thereby then producing a restrictive aspect on the part of each of said first and second signals, and means effective whenever a train is in the section over which second direction traffic approaches said second signal for discontinuing the supply of said feed back energy to said line circuit whereby then also to produce a restrictive aspect on the part of said first signal.

6. In combination, a stretch of railway track which is arranged into successive track sections and over which traffic may pass in either direction, a signal block length of said track which embraces at least one of said sections, first and second signals respectively identified with opposing ends of said block and respectively arranged to govern the entry thereinto of first direction trains and of second direction trains, a control circuit that includes a pair of line conductors

which are coextensive with said block, means at the first signal end of said control circuit for supplying said conductors with master code energy in the form of "on" period pulses that are separated by "off" period intervals and that recur at a first rate normally and at a second rate at certain times, means at the second signal end of said control circuit which receive both said first and second rate pulses of master code energy and which cause said second signal to display its "clear" aspect when and only when said first rate pulses are received and a restrictive aspect at all other times, similarly located means which further supply said circuit conductors with pulses of feed back energy that recur in step with the "off" period intervals of the received master code, means at the first signal end of said control circuit which receive said feed back pulses and which cause said first signal to display its "clear" aspect as long as said reception continues and a restrictive aspect when that reception is interrupted, means effective whenever a train is in said signal block for interrupting said line circuit and thereby then producing a restrictive aspect on the part of each of said first and second signals, means effective whenever a train is in the section over which first direction traffic approaches said first signal for causing said there supplied pulses of master code energy to recur at said second rate whereby then also to produce a restrictive aspect on the part of said second signal, and means effective whenever a train is in the section over which second direction traffic approaches said second signal for discontinuing the supply of said feed back energy to said line circuit whereby then also to produce a restrictive aspect on the part of said first signal.

7. In combination, a stretch of railway track which is arranged into successive track sections, a signal block length of said track which embraces at least one of said sections, first and second signals respectively identified with opposing ends of said block and respectively arranged to govern the entry thereinto of first direction trains and of second direction trains, a control circuit for said first signal which includes a pair of line conductors that are coextensive with said signal block length of track plus the section which adjoins the second signal end of that block, means effective under vacant conditions of both said block and said adjoining section for transmitting over the conductors of said line circuit coded current which causes said first signal to display a proceed indication, an approach relay serially connected in one of said line conductors and held continuously picked up by the said coded current which flows through that conductor, means controlled by said approach relay for supplying energizing current to said second signal when and only when that relay is released, and means responsive to the presence of a train in either said signal block or said adjoining section for interrupting said line circuit whereby then to cause said first signal to give a restrictive indication and whereby then also to release said approach relay and render said second signal active.

HOWARD A. THOMPSON.
